UNITED STATES PATENT OFFICE

2,371,761

SELECTIVE DEVICE

Claude Kittel, Cincinnati, Ohio, assignor to The
Crosley Corporation, a corporation of Ohio

Application July 20, 1937, Serial No. 154,627

1 Claim. (Cl. 177—311)

My invention relates to apparatus for the selective operation of other or parent apparatus; and its primary fields of usefulness lie either in the remote control of the parent apparatus as such, or the more rapid and more convenient selective control of the parent apparatus whether remote or not, such control being much more rapid than would be possible by hand adjustment. My invention will be described in connection with a particular exemplary embodiment which is a device for the automatic, selective, mechanical tuning of a radio set. It is effective for the remote control of any radio set; but remote control is not always the aspect of greatest fundamental utility in a device of this character. By way of example, automobile radio sets have come into wide-spread use. They have to be tuned for station selection, of course; and the tuning is most usually done by the driver of the car while he is driving it. If the tuning is a relatively lengthy operation requiring visual attention on the part of the driver, for an interval at least, his attention is likely to be diverted from the circumstances of his driving.

It will be quite clear, therefore, that if the tuning of an automobile radio set can be made to be carried on automatically in response merely to the pressure of the operator's fingers upon one of a series of buttons which he can select by a sense of touch, the utility of the apparatus and the safety of its use will be very greatly enhanced.

The fundamental objects of my invention may be briefly summarized as constituting the provision of a selector mechanism which will be positive and accurate in its action, the provision of a mechanism which is inexpensive to construct, the provision of a mechanism which the operator can easily set for predetermined stations at his convenience, and an apparatus of such form that it can be attached to an existing radio set without rebuilding or modifying the set itself.

While it will be understood that my mechanism has utility well beyond the particular exemplary embodiment which I have herein chosen for the purpose of making a full, clear and exact description, I shall now proceed to a particular disclosure of the said exemplary embodiment. It will be quite clear to those skilled in the art that modifications may be made in it without departing from the spirit of my invention so as to adapt it to similar or different uses in various other circumstances.

The general objects of my invention which I have set forth hereinabove and others which will be mentioned hereinafter or will be apparent to

one skilled in the art upon reading these specifications, I accomplish by that certain construction and arrangement of parts of which I shall now describe the exemplary embodiment which I have mentioned. Reference is first made to the drawings wherein:

Fig. 1 is a perspective view of an automobile radio set with the devices of my invention assembled to it.

Fig. 2 is an elevational view of the operating mechanism with the cover shown in section. Its relationship to the apparatus illustrated in Fig. 1 is shown by the lines 2—2.

Fig. 3 is a plan or elevational view taken from a different angle with the cover also broken away and certain additional parts broken away. The relationship of this view to the apparatus in Fig. 1 is shown by the lines 3—3.

Fig. 4 is a sectional view through a relay apparatus taken along the lines 4—4 of Fig. 2.

Fig. 5 is a sectional view through the clutch arrangement taken along the lines 5—5 in Fig. 2.

Fig. 6 is a sectional view taken along the lines 6—6 of Fig. 2 and showing the setting mechanism.

Fig. 7 is a wiring diagram with mechanical elements shown diagrammatically.

Fig. 8 is a perspective view of one of the settable discs.

Fig. 9 is a perspective view of the armature of the relay.

The operating mechanism which forms a part of my invention is designed for connection to the shaft of a condenser or condenser gang of a radio set. Its purpose is to move this shaft selectively in response to the pressing of any given one of a series of push buttons, switches or the like, so as to give a predetermined condenser setting quite accurately. While my apparatus may be employed in connection with automatically acting electrical frequency control means which perfect the accuracy of a tuning approximately affected by other means, yet it is designed so that it may be used with radio sets not having such means.

As a consequence, for successful use it must have an accuracy which is very great. Ordinarily there is an allowable error only of approximately one-tenth of a degree in the setting of the condenser shaft. It is an object of my invention to provide means for obtaining such accuracy.

In the practice of my invention I provide a motor of the reversible type; and I couple this motor to the condenser shaft aforesaid. Through a suitable transmission, including a clutch forming a part of or operatively connected with the

transmission aforesaid, I provide a shaft upon which I mount one or more selective means which operate switch means for the control of the motor. The selective means are settable so that they can be arranged to give a predetermined setting of the condenser shaft. The switch operated by each selector disc is of the single pole, double throw type. The reversible motor is controlled by a relay of the double throw type; and the relay is coupled up with the switch aforesaid. This arrangement, and the use of a reversible motor is necessary because the shaft of the ordinary condenser is not a shaft intended for continuous rotation in a given direction. The range of movement of the condenser shaft itself is ordinarily something less than 180° as will be understood. Therefore, in moving from certain positions to other positions, the motor will have to operate in different directions. The switches are energized selectively by the series of push buttons, for example, each supplying power to a different switch. A clutch is provided to prevent coasting of the condenser shaft. Since, in the embodiment to be described, it is necessary to maintain the current to any given selected switch long enough to permit complete response of the apparatus, and since it may not always be convenient for the operator manually to hold the button in depressed position until the tuning is completed, I have provided automatically acting means for the purpose, as will be more fully set forth. The device does not interfere with the normal tuning or operation of the radio set. In adjusting the apparatus for tuning predetermined stations, the radio set is tuned in the ordinary way to a given station, thereupon a selected button is depressed and the corresponding selector disc is rotated until an indicator, provided for the purpose shows that a setting has been correctly made.

Following this brief general description of the apparatus, reference is now made to the diagrammatic showing of Fig. 7 for a clearer understanding of the organization. I have indicated at 10 a suitable source of power, which in an automobile radio set will normally be the automobile storage battery. One terminal of this source of power is grounded as at 11. The other terminal is connected to a power lead 12. One terminal of the motor 13 is connected as at 14 to this power lead. The field 15 of the motor comprises the usual separate windings of a reversible motor. For convenience it has been shown as a tapped winding, the center tap being connected as at 16 to the armature 17 of the motor. The end terminals of the field coil or coils are shown as connected respectively by leads 18 and 19 to contacts 20 and 21 of a relay device 22. This relay has a double throw armature 23 which is grounded as at 24. It will be clear from the arrangement thus far described that the armature of the relay will determine in which direction the motor 13 will run.

The motor 13 is shown as having a shaft 25 bearing a worm 26. A shaft 27 bears a worm wheel 28 which is slidably but non-rotatably mounted thereon. Thus the worm wheel is adapted to serve as a clutch. It is operated by means of an armature 29 having a spring or other suitable means 30 urging the armature into clutch-released position. The magnet 31 is effective in pulling the armature into clutch-engaged position. The winding of the magnet 31 is connected to the power lead 12 by a lead 32. The shaft 27 is intended either for direct attachment to or for connection with the shaft 33 of a condenser or condenser gang through suitable gearing or the like.

A shaft 34 is connected to the shaft 27 by any suitable type of mechanical transmission, such as providing the shaft 27 with a worm, and mounting a worm wheel on the shaft 34 as indicated generally at 35. The shaft 34 bears a number of selector discs 36. It would be possible in a modification of the structure to mount these discs upon some other shaft, such for example, as the shaft 27; but accuracy is promoted in the apparatus by providing for a relatively slow rotation of the shaft 34, as will be readily understood. The discs 36 are settable upon the shaft 34. Each disc bears a pin 37 which engages in a fork 38 on a double throw, single pole switch member 39. Contacts 40 and 41 are provided for the switch and these are connected respectively by leads 42 and 43 to the terminals of windings upon the interspaced relay magnets 44 and 45. The other terminals of the windings on these magnets are connected by leads 46 and 47. The switch part 39 is connected by means of a lead 48 to one push button or other similar switch 49 or a series of these members. The other side of the switch 49 is grounded as at 50 through a lead 51. In the lead 51 a lamp 52 or other suitable indicating means may be placed or removed at will.

As has been hereinabove indicated, it is preferable to provide in connection with the push button 49 a means for holding this switch closed until the mechanism has fully responded to the predetermined setting. This is not a necessary limitation upon my present invention since it is possible to eliminate the provision, if the operator will keep his finger on the push button switch 49 until the mechanism has responded. I have indicated at 53 magnetic means for maintaining the switch 49 in closed position. This magnetic means is connected by a lead 54 to the power lead 12 and by a lead 55 to contact members 56, one on each side of the relay armature 23. A third contact 57 is provided on each side of the armature 23 for connection to a silencer lead 58, which has utility in connection with the operation of the radio set, but is not a necessary limitation upon my present invention.

The magnetic means 53 is so arranged that it will be effective upon any one of the series of push button switches (such as 49) only if that push button is manually depressed.

In the operation of this organization a setting is made by first manually tuning the radio set to a desired radio station. The lamp or other indicating means is placed in the circuit. Then, while maintaining this setting of the radio set, the push button 49, connected to a given one of the selector discs 36 is depressed and the selector disc 36 is manually rotated on the shaft 34 until the switch member 39 lies in the position shown in solid lines in Fig. 7, i. e. a position in which it does not contact either of the contact members 41 or 40.

When this condition is reached the indicating means 52 will register no current. If the means 52 is a light, this light will go out. When this is accomplished a proper setting has been made for the given station.

The resistance of the indicating means 52 is such as to prevent energization of the relay magnets 44 or 45 so long as the indicating means is in the circuit. Thus the operation of setting my device does not tend to start the motor so as to change the pre-set tuning. After all settings have been accomplished, the indicating means 52 may be removed and replaced with a plug or the like to make the lead 51 uninterrupted to ground. An indicating means of low resistance may be left continuously in the circuit 51 if some other means

is provided to prevent operation of the motor during setting. Thus a switch might be provided (and opened during setting) in one of the leads of the clutch magnet 31.

Now if the radio set is tuned to any other station the switch member 39 will not lie in the position shown in solid lines in Fig. 7 but will lie in some other position, either the position shown in dotted lines at 39a or in an opposite position. In either of these positions, however, it will be making contact with one or the other of the contact members 40 or 41, and therefore the motor 13 will be set to go in forward or reverse direction.

Next let it be supposed that the switch 49 is depressed and that the switch member 39 is in the position shown in dotted lines. The switch member 39 will be grounded by the switch 49 and a connection will thus be established through the relay magnet 45. This will attract the armature 23 and a connection will be established through the motor 13 for its operation in a given direction. Simultaneously, of course, the clutch magnet 31 will be energized to engage the clutch, and also the magnetic means will be energized to maintain the push button switch 49 in closed position. The motor will start operating and will continue to operate in the given direction until the pin 37 on the disc 36 engages the fork 38 in the switch part 39 and moves this switch part to the position shown in solid lines in Fig. 7. Thereupon the current connection to the relay will be broken. The current connection to the motor will likewise be broken and the motor will stop. The current connection to the clutch magnet 31 will be broken and the clutch will be thrown out, whereby coasting of the motor 13 will not be imparted to the shaft 21. Likewise the current connection to the magnetic means 53 will be broken by the relay and the push button switch 49 will be released. The device has accomplished the tuning of a radio set to the desired station. It will be understood, of course, that there are as many of the selector discs 36 mounted on the shaft 34 as may be desired. Each disc will have its own switch comprising members 39, 40 and 41, and its own individual push button. Only one of these series of elements is effective at any one time in energizing the selector mechanism, for the reason that but one of the push buttons will be depressed at any one time.

In this way I have provided a simple, effective and accurate mechanism for the purpose described. I come now to a particular description of the exemplary form of my device. In Fig. 1 have shown at 59 an automobile radio set. My selector mechanism may be housed in a casing 60, attached to a bracket 61 arranged for direct connection to the cabinet of the radio set 59. The particular form of the casing and bracket means may be modified to suit different conditions. The casing will be perforated as at 62 to disclose the various selector discs and permit their adjustment. A suitable covering for this opening will usually be provided.

By reference to Fig. 5 it will be seen that the shaft 21 is suitably journaled in the frame of the device and at one end bears a means 63, whereby it may be connected directly to the condenser drive shaft of the radio set 59. The bracket 61 will be so shaped and proportioned as to permit such connection. At the opposite end of the shaft 21 there are connection means 64 to which the usual flexible shaft means 65 of the ordinary dial and control means 66 of the radio

set may be connected. The clutch means which I have hereinabove described is normally disconnected excepting when the selector mechanism is being operated. Thus the shaft 21 forms a direct connection between the flexible drive 65 and the condenser drive of the radio set 59. As a consequence, the tuning and control of the radio set may be accomplished as is usual by means of the device 66 quite irrespective of the presence of my device. My mechanism, therefore, is adjunct to the radio set in this particular embodiment, but unless energized, does not interfere with the operation of the set in the usual way.

The other parts of my apparatus comprise a push button box 67 containing a series of push button switches 68 and provision for the removable insertion of a suitable indicating means, such as a light 52 or a bridging plug. The box 67 has suitable means 70 for mounting it in a position of convenient access to the operator. In the particular embodiment shown this means is a means suitable for mounting the box upon the steering column of a motor vehicle. Such mounting may and usually will furnish the necessary ground connection, although a separate ground connection may be provided, if desired. The push button box 67 is connected with the apparatus in the casing 60 by a suitable plural lead cable indicated at 71. This cable will contain a lead 48 for each of the several push buttons 68 plus the leads 54 and 55 and a ground lead if that is to be separately employed.

The various mechanism which I have hereinabove referred to, is mounted upon a suitable base 72 which may conveniently form one side of the casing 60. The particular manner of mounting the apparatus is not a limitation upon my invention. A particular arrangement is illustrated in the drawings and will be found to be most compact and convenient. The various elements described in connection with Fig. 7 will be recognized by reference to the same index numerals in the other figures. The motor 13 may be an ordinary, commercial, reversible motor.

For the clutch means, I prefer to mount a bracket 73 upon the base 72. The armature 29 is hinged to this bracket. The hinge may be a very simple arrangement, and since the range of movement of the armature 29 is not very great, the spring 30 may engage between an ear 74 on the bracket 73 and an ear 75 on the armature 29. The armature may have a shield 76 of non-magnetic material to prevent this armature from sticking to the core of the magnet 31. The end 55 of the armature is bifurcated or forked as shown at 29a and the fork engages in a groove 28a in the slidable worm wheel 28. This wheel is slidably mounted on a pin 77 on the shaft or upon a collar 78 which is attached to the shaft as shown.

Coming now to the relay, the armature 23 is illustrated in Figs. 4 and 9 as being an angularly bent piece of metal pivoted in a suitable way to brackets 79. A convenient way of doing this is by striking a tongue 80 in the central portion of the armature and passing a pivot means 81 through the opening thus formed. Contact points 82 may be riveted to the armature as shown. Means should be provided for holding the armature normally in an intermediate position. One such means is illustrated in Fig. 4, as comprising strips of resilient metal 83 attached respectively to opposite sides of the armature and having feet bearing respectively against the ends of the coils of the magnets 44 and 45. Other suitable resilient control means may, of course, be employed.

Between the brackets 79, I provide a bridge 85 of insulating material to which resilient conductive means 86 may be attached, bearing the contact means 20, 21, 56 and 57. Suitable connection to these means may be made through terminal members 87, or otherwise.

A selector disc is illustrated in Fig. 8 at 36. In this form, it is a disc of insulating material, the edge of which is knurled or notched as at 88 to facilitate the engagement of the finger therewith for rotating the disc. The disc bears a pin 31, rigidly connected thereto. For mounting the disc upon the shaft 34, I provide a hub 89 with a split resilient collar 90. This collar engages the shaft in such a way as to provide a non-rotatable connection for the purpose of operating the switch members 39 so far as the resistance afforded by the switch members is concerned, but a rotatable connection so far as the operation of the selector discs by the fingers is concerned.

As shown particularly in Fig. 6, the switch members 39 are pivotally mounted in bifurcated studs 91 on an insulating bridge 92 attached to bracket means 93. The contact members 40 and 41 are likewise attached to this bridge by suitable bolts, or otherwise. The switch members 39 move freely in either direction, and the contact members 40 and 41 are so shaped, as shown, as to tend to retain the switch members 39 either when occupying a position such as that shown in Fig. 6 or the opposite position. Since the accuracy of the device will depend in some measure upon the way in which the contact members 40 and 41 come into contact with the switch member 39, it is well to provide positive adjustment means for these contact means. Accordingly, I have shown small angular brackets 94, one for each of the contact means, attached with the contact means to the bridge 92. Each of these small brackets bears set screw or similar adjusting means indicated at 95.

It will be clear that as many of the selector discs 36 may be provided as desired, each selector disc having its own set of switch and contact members and its own push button in the box 67. I have illustrated a device having eight push buttons, and consequently eight selector switch mechanisms and eight selector discs. Ordinarily this will be found to take care of the usual requirements either of an automobile or household radio set, especially when it is remembered that

the device of my invention does not interfere with the usual operation of the radio set and does not interfere with the tuning of the set to stations different from those stations for which the selector mechanism has been set up. My mechanism may be built into any radio sets or attached directly and without difficulty to those already in service. The owner and operator of the radio set makes his own selection of stations for automatic operation. He does this as I have hereinabove indicated, by plugging in the light 52, tuning the radio set to any desired station, selecting a button which is to represent that station, depressing that button whereupon the light 52 will glow, ascertaining the corresponding selector disc 36, and rotating that disc by means of the finger until the lamp goes out, whereupon the device has been set for that station. The operation is repeated for as many stations as it is desired to set up on the automatic mechanism. The lamp 52 may then be removed, and replaced with a bridging plug. The setting may be changed or varied to different stations at any time.

It will be clear that modifications may be made in the arrangement of parts and organization of apparatus to adapt it to different uses, without departing from the spirit of my invention.

Having thus described my invention, what I claim as new and desire to secure by Letters Patent is:

In a control apparatus for positioning a movable member; electric means for actuating said member including a control circuit for said means; a positioning device, including an adjustable element, operable by said means to open said circuit to stop said member at a desired adjustable position; an indicator and a manual selective device for closing said circuit directly or through said indicator, said indicator having an impedance with respect to said first named means sufficient to prevent operation of said means when the indicator is in the circuit; whereby, with said indicator connected in circuit said element may be set by first positioning said member manually at a desired position and then adjusting said element to effect deenergization of said indicator, and thereafter without said indicator in circuit said means may be used for actuating said member to said desired position.

CLAUDE KITTEL.
